BOBBIN SUPPORTING DEVICE

Carl D. Brown, Hopedale, Mass., assignor to
Draper Corporation, Hopedale, Mass., a corpora-
tion of Maine

Application April 14, 1938, Serial No. 201,992

4 Claims. (Cl. 139—251)

The present invention pertains to automatic bobbin changing looms and has more particular reference to bobbin supporting devices for such looms.

Automatic bobbin changing looms commonly include a hopper for holding a reserve supply of bobbins and successively presenting such bobbins in transferring position, a transferrer for transferring the bobbins to the loom shuttle, means for initiating operation of the transferrer, and a swinging bobbin support which may be movable into and out of bobbin supporting position. The said means for initiating operation of the trans- 10 ferrer may include a movable arm having an operative movement which occurs a substantial interval prior to each transferring operation.

As heretofore constructed, swinging bobbin supports have usually been constructed and arranged to be forced out of bobbin supporting position by the bobbin as the latter is transferred to the shuttle. It has been proposed to relieve the transferred bobbin of the strain of thus moving the bobbin support, by moving the latter by connections from the transferrer. Such proposed construction has not proven to be satisfactory, because the transferrer will impart to the bobbin support only a limited movement which may occur too late to accomplish the intended purpose.

A principal object of the present invention is to provide a bobbin changing loom having a hopper, transferrer, swinging bobbin support, and means for initiating the transferring operation as aforesaid, and connections from said trans- 20 ferring initiating means to the bobbin support for moving the latter away from bobbin supporting position well in advance of each transferring movement of the transferrer.

The foregoing and other objects of the invention are accomplished in the construction illus- 30 trated on the accompanying drawing, of which:

Fig. 1 is a view in cross-section of a loom having the preferred embodiment of my invention applied thereto;

Fig. 2 is a similar view illustrating the operation 40 of the parts at the time of transfer; and

Fig. 3 is a horizontal sectional view of certain parts of the mechanism shown on Figs. 1 and 2.

The drawing shows only part of a loom having my invention applied thereto, the parts and 50 mechanisms not shown being of suitable usual construction and not of the present invention. In addition, certain of the parts shown on the drawing are not new, per se, they being of the present invention only in that they may be used 55 in conjunction with the bobbin support operat-

ing means hereinafter described to form a complete operative combination.

The usual lay 1 is mounted to reciprocate toward and from the front of the loom, the front being at the right on Figs. 1 and 2. The lay carries at its right hand end a shuttle box 2 for receiving a shuttle 3. The shuttle contains a bobbin 4 which is adapted to be ejected from the shuttle and replaced by a fresh bobbin whenever the filling supply on the bobbin 4 becomes substantially exhausted.

Reserve bobbins 5, 5' are carried by a hopper, the drawing showing a conventional hopper which includes a hopper stand 6 and a revolving disc 7. The reserve bobbins 5 are supported in 15 the revolving part of the hopper, which is rotated step by step to successively present the bobbins in transferring position. As shown, the bobbin 5' is in transferring position, which is at the bottom of the hopper and directly over the shuttle 20 box 2, as is well known in the art.

The bobbin changing mechanism includes a trans- 25 ferrer 8 which is pivoted on a stud 9 carried by the stand 6. The trans- 30 ferrer includes a rearwardly extending arm having a head 10 positioned 25 directly over the bobbin 5' in transferring position. The trans- 35 ferrer 8 is normally stationary but is periodically given a transferring movement, during which the head 10 moves downwardly to drive the bobbin 5' into the shuttle and expel 30 bobbin 4 therefrom. Such movement of the trans- 40 ferrer occurs wherever the usual latch (not shown) on depending arm 11 is tilted upwardly and is subsequently struck by a bunter on the lay.

The tilting of the aforesaid latch on arm 11 is 35 effected by the usual means for initiating transferring operation of the trans- 45 ferrer. Of such means, the drawing shows only a rod or shaft 12 which extends widthwise of the loom and is supported in bearings such as bearing 13 on the breast beam 14, and an arm 15 which is fixed to the shaft 12. During normal operation of the loom, the arm 15 extends downwardly and thence rearwardly from the shaft 12 as shown by Fig. 1. The shaft 12 is rotated, clockwise on Fig. 1, and arm 15 raised to its Fig. 2 position, an appreciable 40 interval of time prior to each operation of the trans- 45 ferrer. The shaft 12 and arm 15 are returned to their Fig. 1 position after completion of 50 each transferring operation.

The bobbin 5' in transferring position tends to drop down out of disc 7 and then turn around. Such dropping and turning of the bobbins is not prevented by prior swinging bobbin supports, but 55

is entirely prevented by the swinging bobbin support 16 shown on the drawing. The bobbin support 16 is pivotally mounted on the hopper stand 6, as by being suspended from a pivot 17. A head 18 on the lower end of the bobbin support extends laterally underneath the lower edge of hopper stand 6 and disc 7 and underneath the butts of a plurality of the reserve bobbins including bobbin 5¹. A spring 19 yieldingly holds the bobbin support forwardly in contact with a fixed stop 20 on the hopper stand, but permits the bobbin support to be swung rearwardly away from the bobbin supporting position.

The bobbin support 16 as thus described is of usual construction except that I have so constructed the bobbin support and stop 20 that the supporting head 18 is normally appreciably farther forward than in prior constructions. In other words, in my improved construction, the 20 bobbin supporting position of the bobbin support is such that the head 18 extends forwardly well under and in engagement with the bobbin 5¹ which is in transferring position, as suggested by Fig. 1. As thus constructed, the bobbin support 25 positively holds the bobbin 5¹ up in place and thereby prevents the bobbin from dropping down and turning.

When the bobbin support 16 is in bobbin supporting position as shown by Fig. 1, it obstructs 30 the path along which the bobbin 5¹ must move in being transferred to the shuttle. I accordingly provide means for moving the bobbin support rearwardly, away from bobbin supporting position, prior to each transferring operation of the 35 transerrer 8. In the preferred embodiment, shown, such means consists of a Bowden wire 21 which acts as a positive connection from arm 15 to the bobbin support for moving the latter.

The particular Bowden wire shown at 21 includes a head 22 which is fixed in stop 20 and has a plunger 23 bearing against the bobbin support 16. The other end of the wire 21 is provided with a head 24 which is fixed to the breast beam 14 by a clamp 25. The head 24 has a plunger 26 45 therein which plunger engages the rearwardly extending part of arm 15. The construction is such that normally, when arm 15 is down, the plunger 23 is withdrawn within the head 22 and bobbin support 16 is in engagement with stop 20. When 50 arm 15 moves upwardly, it pushes plunger 26 into the head 24 and thus causes plunger 23 to project rearwardly out of the head 22. This pushes the bobbin support 16 rearwardly far enough to permit the bobbin 5¹ to be transferred. Such 55 movement of the bobbin support occurs well in advance of any movement of the transerrer. After the transfer is completed and a new bobbin presented in transferring position, the arm 15,

plungers 26 and 23, and the bobbin support all return to their normal positions.

Having fully disclosed the preferred embodiment of my invention, I claim:

1. In a bobbin changing loom, the combination 5 of a hopper arranged to successively present reserve bobbins in transferring position, a transerrer, a swinging bobbin support pivotally mounted on said hopper for movement into and out of supporting engagement with the bobbin 10 which is in transferring position, means including an arm movable to initiate operation of said transerrer, and means operated by said arm prior to each transferring operation for moving said bobbin support out of engagement with the bobbin 15 which is in transferring position.

2. In a bobbin changing loom, the combination of a rotary hopper arranged to successively present reserve bobbins in transferring position, a normally stationary transerrer having a 20 periodic bobbin transferring movement, a swinging bobbin support pivotally mounted on said hopper for movement to and from bobbin supporting position, means including an arm movable to initiate transferring operation of said 25 transerrer, and positive connections from said arm to said bobbin support for moving the latter away from bobbin supporting position prior to each said transferring operation.

3. In a bobbin changing loom, the combination 30 of a rotary hopper arranged to successively present reserve bobbins in transferring position, a normally stationary transerrer having a periodic bobbin transferring movement, a swinging 35 bobbin support pivotally mounted on said hopper for movement to and from bobbin supporting position, means including an arm having a transfer-initiating movement prior to each movement of said transerrer and a return movement after each said movement of the transerrer 40 is completed, and a Bowden wire connecting said arm with said bobbin support for moving the latter away from bobbin supporting position prior to each transfer and returning the same to said position after each transfer is completed.

4. In a bobbin changing loom, the combination 45 of a rotary hopper arranged to successively present reserve bobbins in transferring position, a normally stationary transerrer, a swinging bobbin support adapted to be moved away from bobbin supporting position before each transferring operation and to be returned to said position after completion of each said operation, means for initiating transferring operation of said transerrer, and a Bowden wire connecting 50 said means with said bobbin support for moving the latter as aforesaid.

CARL D. BROWN.
